(57) **CLAIM**

The ornamental design for a tray, as shown and described.

DESCRIPTION

FIG. 1 is a front top perspective view of a case enclosing a tray showing my new design;

FIG. 2 is an exploded front top perspective view thereof;

FIG. 3 is a front elevational view of a tray;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in FIGS. 1-2 are included for the purpose of illustrating elements of the container that form no part of the claimed design.
